COMBINED TYPEWRITING AND COMPUTING
MACHINE

Henry L. Pitman, Hartford, Conn., assignor to
Underwood Elliott Fisher Company, New York,
N. Y., a corporation of Delaware

Application August 19, 1938, Serial No. 225,762

8 Claims. (Cl. 235—60)

This invention relates to a combined typewriting and computing machine of the Underwood-Hanson class exemplified in my United States Patent No. 1,927,951, dated September 26, 1933.

5 In said machine, typewriting mechanism is operatively connected to a computing mechanism which includes one or more sets of computing wheels, a set of indexable drivers for each set of wheels and a general operator for the drivers. 10 Operation of the numeral-type keys to print an amount, while the letter-feed carriage traverses a computing zone, causes said amount to be indexed in said drivers; the carriage acting at said zone, by means of denomination-selecting 15 mechanism, to shift the drivers seriatim into position wherein numeral-type-key-operated digit-indexing mechanism is effective to set digit-pins in the drivers. The general operator is cycled after the indexing of the drivers to actuate the 20 latter, by means of the set digit-pins, to accumulate said amount in the computing wheels.

Totals are accumulated, according to item classification, in different registers, each of which may be of large grand-total capacity, say a capacity of twelve denominations. With reference to lesser totals, which may never exceed say six denominations, the larger register has an excess capacity.

An object of the invention is to make provision for utilizing said excess capacity or higher denominations of a register for accumulating a lesser total, aside from another lesser total which may be accumulated in the lower denominations of the register. Thus, instead of having say two 35 individual or separate register-units, each of large grand-total capacity, the machine would have, comparatively, a single register of large capacity for large totals, and usable sectionally for accumulating two or more lesser totals.

40 The invention provides novel means for selecting automatically, under control of the carriage, different sections of a register. For example, the carriage, at a given computing zone, may effect, by said means selection of one section of the large capacity register for one lesser-total classification, and may effect, at another zone, selection of another section of said same register for another lesser-total classification. Said novel means include provision whereby the 45 carriage may effect, at a given zone, selection of two or more sections of the register for a total or item involving up to the full-register capacity of denominations. In accordance with these aims, the invention also makes novel provision 50 whereby the denomination-selecting mechanism and denominational tabulating-key mechanism, which are each of full-register range of denominations, are properly correlated to the sectional or full use of the register. By said latter provision, tabulation of the carriage to the units 5 denomination of a computing zone, for example, would cause the carriage at said denomination to select the computing-wheel driver which corresponds to the units denomination of whichever register-section is selected for said zone and shift 10 said driver to the above-mentioned indexing position.

A localized field of register-controls traversed by the typewriter-carriage includes a series of denominational jacks serving to shift the computing-wheel drivers seriatim to said indexing positions, one jack for each denomination of the register of large grand-total capacity. Said localized control field also includes, for each predetermined sectional part of a large capacity register, an element which is selectively engaged by the carriage to determine use of said sectional part of the register at a computing zone.

The invention is applicable to a machine having one or more than one of the large capacity 25 registers, in that it may be applied to operate one or more of said large registers sectionally.

For example, in the herein-illustrated machine, three register units of large capacity are shown, and each register unit is usable by means of the 30 invention as a large capacity register, or sectionally as two lesser capacity registers. Only one series of denominational jacks is provided consonantly with the localization of the field of register-controls; and said single or master series 35 of jacks may have connections ramifying to the several sets of computing-wheel drivers corresponding to the plurality of large capacity register units. The several sets of branches, into which said connections ramify, are normally disconnected from their corresponding sets of computing-wheel drivers. For the purpose of the invention, a set of the computing-wheel drivers may be connected sectionally to its set of branches of the series of denominational jacks, in that, while 45 one section of the set of the computing-wheel drivers is connected to the companion ones of said set of branches, another section of the same set of drivers is not so connected, this being effected under the control of the typewriter-carriage by means of the above-mentioned register-section-selecting elements included in said localized field of register-controls.

Said register-section-selecting elements are controllable by tappets provided on the carriage, 55

and said elements and tappets are proportioned so that the control is coextensive with the number of denominations of the register-section. One of said tappets is provided for each amount-computing column of the work-sheet, and a denomination-selecting tappet, for traversing the set of denominational jacks, is also provided on the carriage for each work-sheet column. The provision of said register-section-selecting elements and tappets to effect control which is limited to the number of denominations of the register-sections controlled by the respective ones of said elements, makes it feasible to make the spacing of the work-sheet columns or zones substantially commensurate with the number of register-denominations used for each column, whereby excessive separation of the work-sheet columns, on account of use of the large capacity register for accumulating small items, is avoided.

20 Certain features of the invention relate to novel means whereby a state-controller, which in the present machine is provided for each register unit of large capacity, serves for predetermining addition or subtraction for either of the register sections as well as for the entire register unit.

This application is in part a continuation of my co-pending application, Serial No. 72,348, filed April 2, 1936, now Patent No. 2,160,487, dated May 30, 1939.

30 Other features and advantages will hereinafter appear.

In the accompanying drawings:

Figure 1 represents a continuation of the left side of Figure 2.

35 Figure 2 is a sectional side elevation of the combined typewriting and computing machine including mechanism in which the invention is embodied.

Figure 3 is a perspective of the mechanism in 40 the computing base comprising the lower portion of the set of denominational selecting trains, the means whereby said trains ramify to a plurality of sets of computing wheel drivers or register bars and the means whereby one or more sets of computing-wheel drivers are connectible sectionally to said denomination trains, some of the parts being sectioned to clarify details.

Figure 4 is a perspective, companion to Figure 3, showing the upper mechanism whereby the 50 typewriter carriage controls the portions of the denomination and register section selecting mechanisms seen in Figure 3.

Figure 5 is a front view of the tappet unit and a register selecting element coextensive with two 55 sections of the register and operatively connected for controlling both sections of the register.

Figure 6 is a perspective of register selecting elements having cam edges coextensive with corresponding register sections and placed one behind the other.

60 Figure 7 is a perspective, partly sectioned, of a portion of the register-section selecting mechanism in the computing base and the means whereby operation of the cycling mechanism 65 serves to insure restoration of said selecting mechanism.

Figure 8 is a front view, partly sectioned, of the devices which sectionally operate the set of couplers that connect the register-bars to the 70 denomination-selecting trains; and shows the means for effecting withdrawal of a state-controller latch at selective operation of said devices.

Figure 9 shows the mechanism of Figure 8 in perspective, the couplers being omitted, and 75 some of the parts sectioned to bring out details.

Figure 10 is a fragmentary perspective of the state-controller and latches therefor, and corresponds to a section on the trace 10-10 of Figure 9.

Figure 11 is similar to Figure 8, the latter representing the state-controller latch withdrawn at engagement of one section of the set of couplers, while Figure 11 shows said latch withdrawn by engagement of another section of the couplers.

Figure 12 is a front view of the register-section-selecting elements and companion slides, and represents the engagement of one of said elements by the tappet-unit.

Figure 13 is a front view of the set of denominations and punctuation jacks, and represents the tappet-unit in engagement with one of the punctuation jacks for actuating a key-lock.

Figure 14 is a side view of the key-lock and the connections from the latter to the set of punctuation jacks.

Figure 15 is a diagram illustrating a work-sheet form and a corresponding set-up of tappet-units on the typewriter-carriage relative to the register-controls.

Figure 16 is a perspective illustrative of variant schemes of connections of sets of distributive racks, for the several registers, to a master set of cross blades.

Figure 17 is a diagram illustrating a set-up of 30 tappets and cam plates for the scheme of connections for the set of distributive racks at the right of Figure 16.

Figure 18 is a diagram of a set-up of tappets and cam plates for the scheme of connections for 35 the set of distributive racks at the left of Figure 16.

In a machine of the Underwood-Hanson class, a typewriter-unit A surmounts a computing base B, Figure 2.

45, 46 and 47 represent, respectively, the key-levers, bell-cranks and type-bars of the numeral-type actions of the typing system, the alphabet type-actions being represented by the alphabet-keys 48. The usual letter-feeding carriage 49 supports a case-shiftable frame 50, in which a platen 51 is journaled, said carriage running upon rails 52, 53 mounted in the typewriter-frame 54.

At operation of any type-action, the usual universal bar 55, escapement-dogs 56, feed-rack 57, 50 escapement-wheel 58 and carriage spring-motor 59 cooperate to letter-feed the carriage 49.

The computing base B may have one or more register-units. The register-unit is of the kind shown in my aforesaid Patent 1,927,951, in that 55 provision for driving its computing wheels 61 oppositely for addition and direct subtraction includes a set of register-bars 62 and idlers 63 permanently in mesh with racks 64 on said register-bars. Said computing wheels 61 normally stand disengaged both from said idlers 63 and said racks 64, Figures 1 and 2, and means for shifting them rearwardly to mesh with said idlers, or downwardly to mesh with said racks, include a shiftable frame 65, in which said computing wheels 61 65 are mounted.

Each register-bar has digit-pins 67, 67'. For setting a digit-pin 67 in a register-bar, the latter must be slightly advanced to align its pins 67 with pin-setting bars 68 which form part of the 70 usual set of Underwood-Hanson pin-setting linkages 69 representing different digits. Each numeral key-lever 45 has a pendant rod 70 to engage an arm 71 of a rock-shaft 72 to rock the latter and thereby actuate the corresponding linkage 69 75

to set, in whichever register-bar is slightly advanced, the digit-pin 67 corresponding to said numeral key-lever 45, each linkage 69 including one of said rock-shafts 72.

5 A denominational tabulating mechanism is represented by denominational tabulating keys 74, Figure 2, and denominational carriage-stops 75. Said denominational keys 74, stops 75, and the cooperating carriage-release means, not 10 shown, may be of the kind shown in Helmond Patent No. 1,858,447, dated May 17, 1932.

The machine is shown as having three register-units, each register-unit having its individual set of register-bars 62 as represented in Figure 3; it 15 being understood that, for driving the companion set of computing wheels 61 reversely, there are associated with each set of register-bars 62 a set of the idlers 63 and the shiftable frame 65 for said computing wheels.

20 The usual reciprocatory cross-bar 76 of the cycling mechanism is common to all of the register-bars 62. Said cross-bar 76 coacts with the digit-pins 67, set in its path by the indexing operation, to advance the register-bars to the indexed 25 extents at the advance stroke of said cross-bar, the computing wheels 61 having been first shifted, as will be explained later on, to engage either the racks 64 or the idlers 63. At the return stroke of the cycling cross-bar 76, the latter engages 30 shoulders 77 of the advanced register-bars 62 to return the latter, the computing wheels 61 having been disengaged first from the racks 64 or idlers 63. The usual spring-devices 78 become effective to retract the returned register-bars 35 sufficiently from said cross-bar 76, after the latter has reached the end of its return stroke, to permit the aforesaid slight advance of the register-bars for the pin-setting operations.

Each of the three register-units is represented 40 herein, by way of example, as having twelve register-bars 62 for accumulating totals up to twelve denominations. For each of said twelve denominations, there is a denominational tabulating stop 75 and its companion key 74. The denominational stops 75 are guided vertically in a housing 79 on the typewriter-frame 54, and, for each computing zone of the carriage 49, the latter presents 45 a counter-stop 80 which is engaged by any upwardly projected denominational stop 75 to arrest the tabulating advance of the carriage at a corresponding denomination in said zone.

A set of denominational jacks 81 corresponds 50 in number to the number of denominations (twelve) in a register-unit, and is grouped behind 55 the set of denominational carriage-stops 75. Said set of jacks is common to the several sets of register-bars 62, and the carriage presents for each computing zone a tappet 82 for depressing said jacks seriatim as the carriage traverses said 60 zone step by step at operation of the numeral-type actions.

Said denominational jacks 81 are guided vertically in a housing 83, which is supported by attachment to the denominational carriage-stop 65 housing 79, by means of a lower bracket 84, and an upper bracket-plate 85 which also spaces and guides said denominational tabulating stops 75. For spacing and guiding the denominational jacks 81 and similar punctuation jacks 86, which 70 are interspersed with said denominational jacks, the housing 83 has an upper slotted guide-bar 87 and a companion face-plate 88, and also has lower guide-plates 89, 90. The denominational jacks 81 are incorporated in the typewriter-unit A and 75 abut against companion rods 91 in the computing

base B, the latter being provided with guide-plates 92, 93, for spacing and guiding said rods 91 at their upper ends. Said rods 91 diverge to correspond in spacing, at their lower ends, with a set of bell-cranks 94 mounted on a fulcrum-rod 95, said bell-cranks 94 connecting said rods 91 to a set of denominational horizontal rods 96, mounted for endwise movement in a frame 97.

Said horizontal rods 96, bell-cranks 94, vertical rods 91 and denominational jacks 81 form a 10 master set of denominational trains, which for the purpose of the invention, may ramify to the register-bars 62 of the several register-units. For 15 accomplishing such ramification use is preferably made of certain devices, set forth in my co-pending application Serial No. 604,691, filed April 12, 1932, now Patent No. 2,090,852, namely, a bed of cross-blades 98, one for each denomination, and sets of distributive racks 99 corresponding 20 to the sets of register-bars 62, and connected by said cross-blades 98 to said rods or master-racks 96; each cross-blade 98 being connected to a master-rack 96 and all of the distributive racks 99 of the same denomination by teeth 100, provided on each rack 96, 99. The cross-blades 25 are rockable upon their lower edges in notches 101 afforded by the frame 97, which is supported by a cross-member 102 of the computing base framework.

For connection and disconnection to and from 30 its companion register-bar 62, each distributive rack 99 has hinged thereto an arm or coupler 103. The full and dotted outlines in Figure 2 represent, respectively, the normal or ineffective, and the effective positions of the coupler 103. 35 In the effective position, the coupler 103, by engagement with a roll 104 on the register-bar 62, operatively connects the latter with the distributive rack 99, so that a slight advance of said 40 rack 99 by the companion carriage-actuated master-denominational train is transmitted to said register-bar 62, to bring its digit-pins 67 under the pin-setting bars 68. With the coupler in ineffective position, said slight advance of the 45 distributive rack 99 has no effect on the register-bar 62.

For selectively using the register-unit sectionally, novel means are provided whereby the set of couplers for the register-unit may be controlled sectionally by the carriage. For example, 50 in the herein shown register-unit of twelve denominations, the section of six couplers 103 for the six highest denominations and the section of six couplers 103 for the six lowest denominations, may be controlled independently of one 55 another. In this way, the section of six highest denominations of the twelve denomination register-unit and the section of six lowest denominations of said register-unit, may be used independently, as for accumulating separate totals in 60 each section.

The novel organization is arranged, by way of example, for using the section of six highest and the section of six lowest denominations of each of the three twelve denomination register-units, herein shown, separately; so that the three twelve-denomination register-units afford six register-sections of six denominations each. For each register-section there is an independent train, whereby the carriage controls the corresponding section of couplers 103. 70

Each register-section-selecting train includes a plate 105 which, as it is traversed by a register-section-selecting tappet 106 on the carriage 49, is in depressed position, Figure 12, for placing the 75

corresponding section of couplers 103 in effective position; the rest of the train including, in order, a slide 107, a push-rod 108, a lever 109, connections from said lever 109 to a rock-shaft 110, and 5 a coupler-section shifter 111 operable by said rock-shaft 110. Said connections are adapted according to the relative placement of said lever 109 and rock-shaft 110, the several levers 109 being grouped, Figure 3, on a common fulcrum rod 10 112 while the array of the several rock-shafts 110 is spread across the machine.

The several cam-plates 105 are spaced parallelly and grouped as in Figure 4, and are guided by upper and lower combs 113 provided on side 15 walls 114 of the housing 83. Each cam-plate 105 has an upper edge contour 115 proportioned relatively to the tappet 106 so that the latter at its engagement with said contour maintains said cam-plate 105 depressed, and the companion section 20 of couplers 103 in effective position, while the carriage traverses a zone of the same number of denominations (six) as the register-section. The tappet 106 depresses the cam-plate 105, by overriding the bevel 116, as the carriage moves 25 to the highest denomination of said zone, and said tappet leaves the cam-plate at a similar bevel for consequent restoration of the cam-plate 105 and the rest of the described train as the carriage moves from the last or lowest denomination of 30 said zone. Said train, together with its section of couplers 103, is restored by a spring 117 which may act on the rock shaft 110 as indicated in Figure 3. The spring-pressed-restoring movement of the train is limited as by abutment of 35 the end of a guide-slot 118 in the coupler-shifter 111 with a guide-stud 119, said rock-shaft 110 having an arm 120, and a stud 121 thereon, engaging a slot 122 of the coupler-shifter 111.

A register-bar-guiding plate 123, attached, for 40 each register-unit, to bosses 102^a on the framework-cross-member 102, mounts the two coupler-shifters 111, for said register-unit, by means of said guide-stud 119 and guide-studs 124, Figure 11. The couplers 103 extend forwardly through 45 an opening 123^a in said plate 123, and the coupler-shifter 111 has, within said opening 123^a, a shoulder 111^a, and also has, behind said plate 123, a portion 111^b to engage the couplers 103.

The connections from the levers 109, on the 50 common fulcrum rod 112, to their companion rock-shafts 110 include levers 125, each engaged by the companion lever 109, as at 126, Figure 3. Said levers 125 are shown arranged in two groups, 55 each group having a common fulcrum-stud 127 projecting from the cross-member 102 of the computing-base framework. The levers 125 in each group may be connected to arms 128 of the corresponding rock-shafts 110 by links 129 or by pin-and-slot connections as at 130, Figure 3. 60 The rock-shafts 110 may be journaled in lugs 131 on said cross-member 102. The push-rods 108, pivotally connected at their lower ends to the levers 109, are guided at their upper ends by plates 132 provided in the computing base 65 B and project above said plates for engagement with the companion slides 107 which work in upper and lower slotted cross-bars 134 provided in the housing 83. The relatively crossed groups of cam-plates 105 and slides 107 are appropriate- 70 ly connected by tabs 135 which may be provided on said slides 107.

Half of the several cam-plates 105 may have 75 their tappet-engaged edges 115 laterally offset as a group from the group of similar edges 115 of the other half of said slides as in Figure 4. The

right-hand and left-hand groups of said tappet-engaged edges 115 correspond inversely with the left-hand and right-hand sections of the several register-units, it being remembered that the carriage moves from the highest to the lowest denomination in leftward direction while the progression of the register denominations from the highest to the lowest is to the right. There is similar transposition in the orders in which the master-racks 96 and the distributive racks 99 10 of the denomination-selecting trains are connected to the bed of cross-blades 98. Each denomination-selecting train is urged by a spring 138^a, attached to the master-rack 96, to normal position determined by a stop, not shown, which 15 engages the cross-blade 98.

The punctuation jacks 86, and a dummy jack 138, connected to a key-locking train, work as a unit by means of a bail 137 pivoted to the housing 83 and articulated to said jacks 86, 138 by 20 pin-and-slot connections 136. The key-lock train, Figures 13 and 14, includes a push-rod 91^a connecting the dummy jack 138 to a bell-crank 94^a which in turn is connected to an arm 139 on a rock-shaft 140, having an arm 141 connected by a link 142 to a rock-shaft 143, Figure 13. Said rock-shaft 143, an arm 144 thereon, a series of tumblers 145, and pendent stems 146 of the numeral-key levers from the usual Underwood-Hanson key-locking devices; the rocking 30 of said shaft 143, effected at a punctuation space, causing said arm 144 to fill the usual gap in the series of tumblers to block said pendent stems 146, and thereby lock said numeral-key levers. The key-lock and punctuation-jack train is 35 restored, as the tappet 82 leaves the punctuation jack, by a spring 147, Figure 2, pulling on an arm 148 of the rock-shaft 140, said arm 148 stopping against a cross-bar 149 of the computing-base framework. The weight of the punctuation jacks 86, 138 and the bail 137 is counterbalanced in part by a spring 150 fastened to the face-plate 83 and pulling on said bail 137.

The tabulating counter-stop 80, the denomination-selecting tappet 82, and the register-section-selecting tappet or tappets 106 are incorporated, for each computing zone, in a tappet-unit 151.

A main supporting rack 152 and an auxiliary rack 153 provided on the carriage 49 serve to support and locate the tappet-unit. A body-block 154 of the tappet-unit has teeth for articulation of the tappet-unit with rack-teeth 158 provided along the bottom of the main rack 152. A strip 159 of resilient metal, attached to the top 55 of the body-block 154, as by screws 160, is formed into a clip 161 at its ends, to engage a groove 162 in the top of the main rack 152 for removably attaching the tappet-unit to said main rack. Said strip 159 has teeth 163 whereby the tappet-unit 60 engages the auxiliary rack 153. The tabulating counter-stop 80 is formed integrally with the body-block 154. The denomination-selecting tappet 82 is driven into the body-block 154.

For differential placement therein of the register-section-selecting tappet or tappets 106, the bottom portion of the body-block 154 is provided with a sufficient number of transverse slots corresponding in spacing to the cam-plates 105. Keeper-plates 172 retain the tappets 106 in the 70 block 154.

A roller 177 upon the tappet-unit 151, fits a track 178, supported by the housing 83, to brace the tappet-unit 151 as it traverses the localized group of register-controls comprising the reg- 75

ister-section-selecting cam-plates 105, and the jacks 81, 86.

The tappet-unit 151 has a tooth 179 for rocking a cycling trip-lever 180 traversed by the carriage 49 and pivotally supported by the plate 88. Said lever 180, incorporated in the type-writer-unit A, is connected as at 181 to a train, similar to the denominational jack-train, and comprising rods 176, 176^a, and a bell-crank 182, Figure 4, to work a lever, in the computing base B, comprising an arm 183 operative to trip a clutch-mechanism, not shown, to connect a suitable power drive, not shown, to a shaft 188 for cycling the latter by power. Said shaft 188 may have a connection to drive the general operator which includes the register-bar-driving cross-bar 76 for reciprocating the latter at a revolution or cycle of said shaft 188. Said connection, not shown, may be of the kind shown in my co-pending application No. 15,789, filed April 11, 1935, and briefly described, comprises a crank, not shown, on said shaft 188 and a pitman, not shown, connecting said crank to one of the side plates 189 which connect said cross-bar 76 to the usual side-racks 190 of the general operator, said side-racks 190 being each geared to the usual cross-shaft 191, Figure 2, as described in my aforesaid Patent No. 1,927,951. Said clutch mechanism may be as shown in Patent No. 1,299,646 to Wood, dated April 8, 1919.

The diagram at Figure 15 exemplifies a set-up, on the carriage 49, of the tabulating counter-stops and tappet devices relative to the localized group of the tabulating and register controls 75, 81, 105, said set-up being for a work-sheet form 193. The first column of said form 193 is for amounts which total no more than six denominations and are to be entered, by way of example, in the register section consisting of the six lowest denominations of the first twelve-denomination register-unit from the left in the computing base. The set-up includes accordingly for said first column a tappet-unit (151¹ in Figure 15), which has, besides the counter-stop 80 and the denomination-selecting tappet 82, a register-section-selecting tappet 106 located on said unit 151¹ for engaging the edge 115 of the second cam-plate 105 from the front, Figures 4, 15.

At the operation of one of the tabulating keys 74 of the six lowest denominations, the carriage will advance and be arrested as the counter-stop 80 of said unit 151¹ strikes the carriage-stop 75 projected by the operated tabulating key 74. At release of said tabulating key 74 and retraction of the stop 75, the carriage settles as usual at the corresponding denomination, and said second cam-plate 105 from the front will have been depressed by the tappet 106 of said unit 151¹, and thereby the section of couplers 103, controlled by said second cam-plate from the front, will have been moved to effective position to connect the section of register-bars of the six lowest denominations of the first register-unit to the corresponding denomination-selecting trains, which it will be remembered include the jacks 81 traversable by the tappet 82 of said unit 151¹.

It will be seen now that said tappet-unit 151¹ can select no other register-section in the computing base but the one represented by its particularly placed tappet 106, namely, the section consisting of the six lowest denominations of the first register-unit from the left. The desired register-section having thus been selected for said first column, the printing of an amount

proceeds as usual, and concomitantly the amount is indexed in the appropriate ones of the register-bars 62 of the six lowest denominations of the first register-unit. Following the printing and indexing of the amount, the general-operator cross-bar 76 is reciprocated to actuate the indexed register-bars to accumulate the indexed amount in the computing wheels 61, which become engaged with the idlers 63 or racks 64, the accumulation being limited to the computing wheels of the six lowest denominations of the first register-unit, inasmuch as no total of amounts entered in said first column exceeds six denominations.

Suitable carry-over mechanism (not shown) may be of the kind shown in my aforesaid Patent No. 1,927,951.

The second column of the work-sheet form 193 in Figure 15 is also for amounts or totals not exceeding six denominations, and, by way of example, said amounts are to be accumulated in the register-section consisting of the six lowest denominations of the middle register-unit of twelve denominations in the computing base B. A tappet-unit (151² in Figure 15 for said second column is accordingly provided in the set-up and has, besides the counter-stop 80 and denomination-selecting tappet 82, a register-section-selecting tappet 106 located to engage the cam-edge 115 of the fourth cam-plate 105 from the front, Figures 4, 15. Thus, by tabulating the carriage to the second column position and desired denomination therein, said fourth cam-plate 105 will become depressed and the corresponding section of couplers 103 become moved to effective position to connect the section of register-bars 62, consisting of the ones of the six lowest denominations of the middle register-unit, to the corresponding denominational trains. The amount printed in said second column will, therefore, be indexed and accumulated in the register-section consisting of the six lowest denominations of said middle register-unit.

The third column of the form 193 is also for amounts or totals not exceeding six denominations, said amounts to be entered, by way of example, in the register-section consisting of the six highest denominations of the middle register-unit. The six lowest denominations of tabulator-keys 74 and corresponding stops 75 are used to tabulate the carriage to the third column position irrespective of the use of a register-section consisting of the six highest denominations of a register-unit. A tabulating stop 80 is therefore placed, for said third column, with reference to said six lowest tabulating denominations. But the register-section-selecting tappet 106 and denomination-selecting tappet 82 are offset six denominations (not counting punctuation spaces) to the right of said third-column tabulating stop 80. The provision for the third column, in the set-up of tappet-units on the carriage, may therefore include, Figure 15, two complementary units 151³. One of said complementary units 151³ has only the counter-stop 80 and is placed on the carriage with reference to the aforesaid use of the tabulating stops 75 of the six lowest denominations. The other complementary unit 151³ has a denomination-

selecting tappet 82, and also has a register-selecting tappet 106 placed to engage the edge 115 of the third cam-plate 105 from the front, Figure 4, said other complementary unit 151³ being placed to effect the aforesaid offset, of its tappets 75

82, 106, of six denominations to the right of said counter-stop 80.

By the described offsetting of the counter-stop 80 from the tappets 82, 106 for said third column, the section of denominational jacks 81, 5 which comprises what are ordinarily the six highest denominations of the full complement of jacks 81, is denominational correlated to the section of tabulating stops 75 of the six lowest 10 denominations. For example, if the tabulating key 74 for the tens of hundreds denomination is 15 pressed to position the carriage for typing, in the third column of the form 193, the amount 75.49, the tabulating stop designated s in Figure 15 will be projected and will arrest the resulting advance of the carriage by engaging the counter-stop 80 of the unit 151³ which is offset 20 as described, relatively to the tappets 82, 106 for said third column. With the carriage thus positioned, the denomination jack marked d, in 25 Figure 15, and the third cam-plate from the front will have become depressed, respectively, by said third-column tappets 82, 106, and therefore, as the amount 75.49 is printed, it will become concomitantly indexed in the register-section 30 consisting of what are ordinarily the six highest denominations of the middle register-unit of twelve denominations.

The fourth column of the form 193 is for 35 amounts or totals up to twelve denominations, said amounts being entered, by way of example, in the right-hand register-unit of twelve denominations. A tappet-unit (151⁴ in Figure 15), for said fourth column, includes, besides the 40 counter-stop 80 and the denomination-selecting tappet 82, two of the register-section-selecting tappets 106 placed to respectively engage the edges 115 of the fifth and sixth cam-plates 105 from the front, Figures 4 and 15. Thus, while the carriage traverses the six highest denominations for said fourth column of the form 193, the fifth cam-plate 105 from the front will be depressed, and thereby the section of six couplers 103 of highest denominations will have 45 become shifted to effective position to connect the six highest denomination-register bars 62 of the right-hand register-unit to the corresponding section of denominational trains. Then, as the carriage reaches and traverses the six lowest denominations for said fourth column, the sixth cam-plate will become depressed, and thereby, in turn, the six lowest denomination-register bars 62 of said right-hand register-unit will become operatively connected to their 50 corresponding section of the denominational trains.

Full use of a register-unit, as, for example, for the twelve-denomination fourth column of the form 193, may also be provided for, by having, instead of the two cam-plates 105 for said 55 unit, a single cam-plate 194, Figure 5, having a cam-edge 194^a substantially coextensive with all of the denominations of the register-unit. Only one cam-plate-depressing tappet 106 is provided in the tappet-unit 151 for depressing said cam-plate 194, and the latter is connected to simultaneously depress both slides 107 for said 60 register-unit, and thereby simultaneously move both sections of the couplers 103 for said register-unit into effective position which is maintained while the carriage traverses a zone at which the full register-unit is used. 195, Figure 5, represents an offset with which the cam-plate 194 is provided to reach the offset tab 135 65 of one of the slides 107, the tab of the other 70 75

slide being directly under the cam-plate 194. A keeper-bolt 192 extends through the cam-plates 105, and is removable for interchange or replacement of said cam plates.

It will be evident in the foregoing description 6 concerning Figure 15 that the accumulation of some amounts in one section of a register-unit and of other amounts in another section of the same register-unit is exemplified by the accumulation 10 of the second and third column amounts respectively in the right and left sections of the middle register-unit.

It will also be evident that the provision for 15 sectional use of the large register-units makes it feasible to have the first three columns of 193 each no wider, substantially, than the illustrative six denominations (plus punctuation spaces) needed for the amounts entered in said first three columns.

Provision for sectional use of the register-units 20 also extends the range of usefulness of the machine. For example, where previous machines, of the Underwood-Hanson class, having three registers, each of say twelve denomination capacity, could only accumulate three totals, by 25 using all three of said register-units, even though none of the totals exceeded six denominations, the present machine can accumulate said three totals of six denominations each, by using only two of the three register-units, and still have 30 left for other totals a section of one of said register-units and the entire third register-unit, the latter being usable either sectionally for small totals, or in full for totals up to twelve denominations.

Regarding the described offsetting of the tabulating counter-stop 80 from the tappets 82, 106, by means of the complementary units 153³, Figure 15, it will be observed that such offsetting is 35 primarily on account of arranging the connections of the cross blades 98 to the distributive racks 99 in simple echelon formation for full 40 register operation as in said Patent No. 2,090,352. Thus, referring to the middle set of twelve distributive racks 99, Figure 16, the connections 45 379 thereof to said blades 98 form a single line in echelon between the highest and lowest of the twelve distributive racks. The slope of the line is, of course, opposite to that of a similar line of connections 380 from the cross blades 98 to the master racks 96, Figure 16, in order to 50 effect the usual transposition of denominational sequence of the distributive racks 99 as compared with the master racks 96.

It will be explained, now, how a register section 55 comprising the higher denominations of a full register may be used without offsetting the tabulating counter-stop 80 from the companion tappets 82, 106.

Thus, referring to the set of distributive racks 60 99 at the right of Figure 16, there may be two lines of connections 381, one line for each section of six denominations of said right hand set of twelve distributive racks 99, and disposed so that each section of six racks 99 is connected 65 to the same section of six cross blades 98, of lower denominations. Further, the cam plates 105 for the two distributive-rack-sections, of six denominations each, are disposed so that their cam edges 115^a are directly one behind the other 70 as in Figures 6 and 17, instead of being laterally offset as in Figure 15. Thus, Figure 17, the cam edge 115^a for the register section that ordinarily comprises the six highest denominations of a twelve denomination register is directly be- 75

hind not only the group *l* of six denominational jacks *81* of lowest denominations but it is also behind the group *L* of six tabulating stops *75* of lowest denominations. Referring to Figure 17, the tappet unit *151⁶* has a register selecting tappet *106* for engaging the front cam edge *115^a* associated with, say, the six lowest denominations of the register and said unit *151⁶* also includes a tabulating counter-stop *80* and a denomination selecting tappet *82*. The unit *151⁶*, Figure 17, has a tappet *106* placed to engage the next cam edge *115^a*, associated with the register section of six highest denominations. This unit *151⁶* itself includes a tabulating counter-stop *80* since the latter need not be offset.

The arrangement of connections *381* for the right hand set of twelve distributive racks *99*, Figure 16, is suitable where the latter are used only sectionally. Where operation of a register up to full capacity is desired, an extra register (the middle register of Figure 16) may be provided and may have its distributive racks *99* connected as shown for the middle set in Figure 16. In Figure 17, the cam plate *105* having a full length cam edge *115^b* is associated with said middle register and the corresponding tappet unit *151⁷* has a tappet *106* for engaging said edge *115^b*.

The full set of distributive racks *99* at the left of Figure 16 illustrates another scheme of connections to the cross blades *98* devised for both sectional and full register operation without involving offsetting of any tabulating stop *80* from its companion tappets *82, 106*. In said scheme there is one line of connections *382* whereby, for full register operation, all of the twelve distributive racks *99* are connected to all of the twelve cross blades *98* in a manner similar to the connections for the middle set of racks *99*, Figure 16. In addition, there is another line of connections *383* whereby the distributive racks *99* of six highest denominations of the full set are connected to the cross blades *99* of six lowest denominations. For sectional use of the register corresponding to the full set of distributive racks *99* at the left of Figure 16, the cam plates *105* associated with the two sections are disposed, Figure 18, with their cam edges *115^a* one directly behind the other and both directly behind the group *l* of six lower jacks *81* and the group *L* of six lower denominational tabulating stops *80* so that said groups *l* and *L* work in conjunction with either cam plate edge *115^a*. This scheme provides for using the section of six highest denominations of the full register, through the six lower denominational jacks *81*, without necessitating offsetting of the tabulating counter-stop *80* from the jack engaging tappet *82*. In Figure 18 the tappet unit *151⁸* has a tappet *106* to engage the foremost cam edge *115^a* associated with, say, the section of six higher denominations; and the tappet unit *151⁹* has a tappet *106* to engage the other cam edge *115^a* associated with the section of six lower denominations. Said tappet unit *151⁸*, for the section of higher denominations, includes the tabulating stop *80*. For full register operation, a tappet unit *151¹⁰* may have two tappets *106* placed to engage successively two cam edges *115^a* offset laterally as in Figure 18 so that the edge *115^a* associated with the six higher denominations is engaged first.

Referring to said set of distributive racks *99* at the left of Figure 16, it will be perceived that the section of six higher denominations of said racks *99* is connected by the connections *382* and

383 both to the section of six lower denominations and to the section of six higher denominations of the cross blades *98*. Therefore, said section of six higher denominations of said racks *99* may operate either through the lower section *l* of jacks *82* for sectional register operation or through the higher section *h* of the jacks *82* for full register operation. Thus, when operating one of the higher set of distributive racks *99* through the higher section *h* of jacks *82*, as at *10* full register operation, a corresponding one of the distributive racks *99* of the lower section is concomitantly operated. But such concomitant operation of one of the distributive racks *99* of the lower section may be idle since at that time *15* the active tappet unit *151⁷* has only one of the two tappets *106* effective, namely, the one for the right hand (Figure 18) cam edge *115^d* for the higher section of racks *99*, and hence renders effective only the corresponding section of couplers *103*, the other or lower section of couplers remaining depressed. Similarly, when one of the lower section of distributive racks *99* is operated through the lower set *l* of jacks *82* a corresponding one of the distributive racks *99* of the higher section is concomitantly, but idly, operated.

It will be understood that each cam plate *105*, having the cam edge *115, 115^a, 115^b, or 115^c*, is operatively connected to the appropriate coupler controlling plate *111* by means of the appropriately arranged tab *135*, plate *105* and the train comprising *108, 109* etc. to the crank stud *121* for the coupler controlling plate *111*.

Following the indexing of an amount in the register-bars *62* and preceding the advance of the latter by the general-operator cross-bar *76*, the entire set of computing wheels *61*, in each twelve denomination-register unit which has been called into play by means of the carriage-controlled register-section-selecting trains, is shifted into mesh with either the corresponding idlers *63* or the register-bar racks *64*. For this purpose, and for disengaging said computing wheels precedent to the return of the register-bars, use *40* may be made of the computing-wheel shifting mechanism and state-controlling mechanism disclosed in my co-pending application No. 607,275, filed April 25, 1932, now Patent No. 2,091,717, dated August 31, 1937. Said mechanism may be *50* briefly described as follows:

Each twelve-denominations unit has a state-controller *230*, Figures 1, 2, 8, 9, 10 and 11, extending fore and aft along the bottom of the computing base *B* and urged forward by a spring *231*. An upright latch-rod *232* projecting through a guide-plate *233* normally engages a shoulder *234*, Figure 10, of the state-controller *230* to keep the latter in neutral position. The upright latch-rod *232* is further guided by the register-guide-bar plate *123* and pins *235*, Figure 8, therein. Headed screws *236* slidably support the state-controller *230* at its rear end-portion and at its forward end-portion the state-controller works *237* in a guide *239* provided on a frame-cross member *239*, Figure 1.

A cam *238*, Figure 9, on the state-controller works a cross-slide *239^a*, mounted on the guide *237*, Figure 1, whereby a U-shaped member *240*, *70* connected to said cross-slide *239^a* and splined to a computing-wheel-shifting rock-shaft *241*, is shifted along the latter to engage either a yoke *242* having side arms *243*, or an arm *244*. Said yoke *242*, with its side arms connected to the *75*

shiftable computing-wheel frame 65 by links 245, is normally loose on the rock-shaft 241 as is also the arm 244, the latter having a slot 246 for its connection to said frame 65 at 247. Upon the 6 retraction of the latch-rod 232 the resulting forward shift of the state-controller 230 is limited by a secondary latch-rod 249 engaging a shoulder 250, Figure 10, of said state-controller. Such limited state-controller shift acts, through the 10 cross-slide 239^a and companion member 248, to couple the arm 244 to the computing-wheel rock-shaft 241. Upon retraction of a secondary latch-rod 249 the resulting further shift of the state-controller 230 acts to couple the yoke 242, 243, 15 instead of the arm 244, to the computing-wheel rock-shaft 241.

With the arm 244 coupled to the rock-shaft 241, as a result of retracting only the primary latch-rod 232, the rocking of said shaft 241 clockwise of 20 Figure 1 will swing the frame 65 downwardly about on axle 251 for the idlers 63, to mesh the computing wheels 61 with the racks 64 for additive rotation of said wheels. With the yoke 242, 243, instead of said arm 244, coupled to the rock-shaft 241, as a result of retracting also the secondary latch-rod 249, the clockwise rocking of the 25 shaft 241 will shift the frame 65 rearwardly to mesh the computing wheels 61 with the idlers 63 for subtractive rotation of said wheels. The rock-shaft 241 remains rocked during the advance of the register bars 62. Before the return of the latter, said shaft 241 is rocked to its normal position, to thereby unmash the computing wheels 61 from the racks 64 or idlers 63. By means of 30 operating connections, not shown, said rock-shaft 241 is worked in timed relation to the reciprocation of the general-operator cross-bar 76. By means of other connections not shown, a state-controller restorer 252 is worked in conjunction 35 with the return stroke of the general-operator cross-bar 76 to restore the state-controller 230, cross-slide 239^a and rock-shaft-coupling member 240 to normal positions, following the unmashing of the computing wheels 61, the latch-rods 232, 249 being urged by springs, not shown, to reengage 40 the restored state-controller.

The secondary latch-rods 249 for the several register-units are connected as at 254, Figure 2, to a rock-shaft 255 for joint retraction by the rocking of said shaft 255. Said shaft 255 may be rocked, to retract said latch-rods 249, by means of a manually operable subtraction-key mechanism not shown, or a carriage-controlled subtraction-setting mechanism not shown, said mechanisms being of the nature described in my said co-pending application No. 607,275, now Patent No. 2,091,717.

Novel provision is herein made whereby the addition latch-rod 232 of a register-unit is retracted conjointly with the carriage effected selection of a section of said register-unit, but irrespective of which section is selected, and said provision is shown embodied in the following devices, Figures 7, 8, 9 and 11.

65 A latch-rod-retracting lever 256 is fulcrumed behind the register-bar guide-plate 123 on a stud 257 and is articulated to the primary latch-rod 232, as at 258, Figure 9. At operation of one of the register-section-selecting trains for the 70 register-unit by means of the carriage-tappet 106, said lever 256 is rocked clockwise from the Figure 10 position to retract the latch-rod 232. For this purpose, the stud 121 of the coupler-shifter-actuating rock-shaft 110 of each train is operatively connected to said lever 256; said lever 256 being

directly engageable by the stud 121 of one rock-shaft 110, and the stud 121 of the other rock-shaft 110 of the register-unit engaging an intermediate lever 261, fulcrumed behind the plate 123 on a stud 262, said intermediate lever, in turn, engaging said latch-rod-retracting lever 256. As the left-hand coupler-shifter 11, at Figure 8, is raised by its rock-shaft 110 to move the corresponding section of couplers 103 to effective position, the stud 121 directly engages the lever 256 and rocks the latter to retract the latch-rod 232 as illustrated in Figure 8. Should the right-hand coupler-shifter 11 be raised by its rock-shaft 110, the latter, through its stud 121, will rock the intermediate lever 261 counter-clockwise, thereby, in turn, rocking the latch-rod-retracting lever 256 to retract the latch-rod 232 as in Figure 11.

Thus the operation of selecting either section of the register-unit retracts the latch-rod 232 for resulting release of the state-controller 230 to predetermine additive rotation of the computing wheels 61. If, in addition to the thus effected retraction of the primary latch-rod 232, the secondary latch-rod 249 is also retracted, as by operation of the subtraction-key mechanism, the resulting further movement of the state-controller 230 predetermines subtractive, instead of additive, rotation of the computing wheels 61.

Provision for insuring restoration of the couplers 103 includes a cam-slide 259 which has 30 notches 259 forming cams 260 for engaging the studs 121 of the coupler-shifting rock-shafts 110. Said cam-slide 259 is slidably guided by slots 263 of the framework cross-member 102 and by studs 264 on the frame 97 and is yieldably held by a 35 spring 266 in normal position, Figure 3, in which said notches 259 clear said rock-shaft studs 121. A push-rod 253^a, connected to said cam-slide 259, is slidable in a lug 102 of said cross-member 102 and has its end normally in the path of a cam 40 264^a formed by a slot 266 in the general-operator rack 190. Thus, during the advance stroke of the general operator, said rack-cam 264^a acts to displace said cam-slide 259 to the Figure 8 position to depress any stud 121 which may have remained 45 in raised position, thereby insuring restoration of the coupler-shifters 111 and couplers 103 to their normal ineffective positions.

It will be remembered that the bell-cranks 94, 94^a and 182, forming part of the denomination 50 and punctuating jack-trains and cycle-tripping train, have the common fulcrum-rod 95, and that the levers 109 of the register-section-selecting trains have the common fulcrum-rod 112. By appropriate displacement of said fulcrum-rods 55 from their normal positions, a slack is formed in said trains relatively to the tappets 102, 106 and the cycle-tripping tooth 179 on the carriage, and said trains are thereby disabled. A rock-shaft 265, journaled in posts 266, on a cross-bar 267 of the computing-base framework, Figure 3, is rockable to effect displacement and restoration of said fulcrum-rods 95, 112, said rock-shaft 265 having upright arms 268, supporting the fulcrum-rod 95, and horizontal arms 269, from 60 which links 270 depend and support the fulcrum-rod 112.

A latch-arm 271 is mounted on a rock-shaft 272 and is connected to the latter by a one-way yieldable connection, comprising a spring 273 and 70 rock-shaft arm 274. Said latch-arm 271 normally engages a step 275 of an arm 276 of the fulcrum-rod controlling rock-shaft 265, to hold the latter and the fulcrum-rods 95, 112 in the normal, Figure 2, positions, whereby the aforesaid trains 75

- are in condition for actuation by the carriage. Upon withdrawing the latch-arm 271 therefrom, said arm 276 is turned by the weight of the parts, and thereby rocks its shaft 265 until a second 5 step 277 on said arm 276 stops against the withdrawn latch-arm 271. Thus the withdrawal of said latch-arm 271 results in the fulcrum-rod 95 being instantaneously displaced rearwardly and the fulcrum-rod 112 downwardly to instantaneously disable said trains. Upon disablement of 10 said trains the cam-plates 105 and slides 107 may drop to position wherein said slides rest upon a cushioning pad 279a provided upon one of the slide guiding cross-bars 134. Slotted guides 278 15 on the cross-bar 267 guide the pendently-supported fulcrum rod 112. Other features relating to the disablement and restoration of said trains are described in my aforesaid application, Serial No. 72,348 now Patent No. 2,160,487.
- 20 What is claimed is:
1. In a machine of the character described, the combination of a carriage, a multiplicity of indexable register-bars of consecutive denominations forming part of a register-unit, said bars 25 shiftable individually to an index-receiving position, a state-controller associated with said register-unit and conditionable for a certain computing state, a series of denominational driver-shifting trains, traversable by said carriage for shifting 30 said register-bars seriatim, said trains including couplers actuatable for operatively connecting the trains to the register-bars, a plurality of selectively operable register-section-defining coupler controllers, each serving to independently 35 bring into use one or another predetermined section of the couplers consonantly with sectional use of the register-unit, and means operatively connecting said state-controller to said coupler-controllers whereby concomitantly with use of 40 either section of the couplers said state-controller is conditioned.
  2. In a combined typewriting and computing machine, the combination with digit-type keys, a step-by-step feeding typing carriage coacting 45 with said keys, and a set of indexable computing-wheel drivers for a register-unit having a multiplicity of consecutive denominations, one driver for each denomination, said drivers being shiftable individually to a position wherein they are 50 indexable by means of said keys preparatory to cycling said drivers, of a set of driver-shifting jacks, one jack for each driver, a plurality of jack-traversing tappets on said carriage for different computing zones for traversing and actuating said 55 jacks seriatim, all of said drivers being normally operatively disconnected from said jacks, said tappets being separated, for certain narrow-column typing, by carriage step units less in number than the number of said consecutive denominations, wherefore two sections of said jacks 60 may be actuated simultaneously, devices individually operable to operatively connect said jack-sections to corresponding sections of the set of computing-wheel drivers, and means arranged 65 on the carriage in correlation with said tappets to operate said devices selectively to determine whether or not the jack-section operated by one or the other tappet is operatively connected to the companion drivers for shifting the latter.
  - 70 3. In a machine of the character described having a computing register for a multiplicity of consecutive denominations, the combination with a set of indexable register-wheel drivers, one driver for each of said denominations, shiftable seriatim to an index-receiving position, of a set of 75 denominational driver-shifting jacks, a carriage having a denomination-selector to engage said jacks seriatim, a plurality of individually operable register-section-defining elements disposed in staggered relation in the path of carriage travel 5 so as to be offset, one from the other, transversely of said path and along said path, and a plurality of groups of jack-and-driver connectors, each group associated with a companion register-section-defining element and operable by the latter 10 to connect, operatively, a predetermined section of said set of drivers to a companion section of said set of jacks, and means on the carriage to operate said register-section-selecting elements selectively, whereby to determine, relative to traverse of a section of said set of jacks by said denomination-selector, whether said section of 15 jacks will be operatively connected to the companion section of said set of drivers.
  4. In a machine of the character described, the 20 combination of a unitary set of indexable computing wheel drivers for a single register unit of an extensive number of denominations, one driver for each denomination, a plurality of denominational jacks less in number than the number of 25 computing wheel drivers in that said plurality of jacks is common to different sections of said unitary set of drivers, a carriage feedable in denomination-selecting steps, means enabling the carriage to operate said jacks seriatim at said 30 steps, and means controlled by the carriage to connect operatively a predetermined one or other of said sections of drivers to said jacks, said carriage and jacks serving to advance the drivers seriatim to index receiving positions and said 35 jacks and drivers normally being operatively disconnected.
  5. In a machine of the character described, the combination of a unitary set of indexable computing wheel drivers for a single register 40 unit of an extensive number of denominations, one driver for each denomination, a set of denominational jacks corresponding in number to said denominations, a carriage feedable in denomination selecting steps, a set of denominational tabulating stops for said carriage corresponding to a predetermined section of said 45 jacks, a plurality of register section defining devices selectively operable to connect a predetermined one or other section of said drivers to 50 said section of jacks for split register operation, said set of tabulating stops, section of jacks, and register section defining devices being offset one from the other transversely of the path of carriage travel, and a computing zone defining unit 55 on said carriage presenting a jack operating tappet, a register section selecting tappet and a tabulating tooth, said unit being adaptable for selecting either section of the register by placing the register selecting tappet thereon to engage 60 the appropriate register-section-defining device.
  6. In a machine of the character described, the combination of a unitary set of indexable computing wheel drivers for a single register unit of an extensive number of denominations, 65 one driver for each denomination, a set of denominational jacks corresponding in number to said denominations, a set of intermediate elements, one between each jack and corresponding driver, said set of elements including a set 70 of couplers operable sectionally to connect operatively a predetermined one or other section of said drivers to said jacks, said elements being connected individually to corresponding ones of all of said jacks by a corresponding series of 75

connections and a section of said elements being additionally connected only to a section of said jacks by a correspondingly limited series of connections, a carriage feedable in denomination selecting steps and adapted to actuate said jacks seriatim, and means enabling the carriage selectively to operate said set of couplers sectionally.

7. In a computing machine of the character described, the combination with a set of indexable computing-wheel-drivers, there being one driver for each of a multiplicity of consecutive denominations for a single register, and a normally disconnected from said denominational devices operable by said carriage in denominational order for shifting said drivers individually to index-receiving position, said drivers being normally disconnected from said denominational devices, a plurality of register-section-defining devices selectively operable to connect one or another of predetermined sections of said set of drivers to said denominational devices for split register operation, and means on the carriage to engage and operate one or another of said

register-section-defining devices according to a predetermined plan.

8. In a computing machine of the character described, the combination with a plurality of sets of indexable computing-wheel-drivers, the drivers in each set corresponding in number to a multiplicity of consecutive denominations for an associate register of large denominational capacity, said drivers being individually shiftable to index-receiving position, a denomination-selecting carriage, a single group of denominational jacks operable seriatim by said carriage for shifting the drivers to said position, connections extending from the group of jacks to the several sets of drivers and including, for each set of drivers, a plurality of register-section-defining devices selectively operable for connecting one or another predetermined section or all of any set of drivers to said jacks, and means enabling the carriage to engage and operate said register-section-defining devices selectively.

HENRY L. PITMAN.

CERTIFICATE OF CORRECTION.

Patent No. 2,202,671.

May 28, 1940.

HENRY L. PITMAN.

It is hereby certified that error appears in the printed specification of the above numbered patent requiring correction as follows: Page 10, first column, line 12-13, claim 7, for "de- normally disconnected from said denominational" read --denomination-selecting carriage, of denominational--; and that the said Letters Patent should be read with this correction therein that the same may conform to the record of the case in the Patent Office.

Signed and sealed this 30th day of July, A. D. 1940.

(Seal)

Henry Van Arsdale,
Acting Commissioner of Patents.
